Inventor,

Thomas W. Moore,

By A. L. Jackson,

Attorney

UNITED STATES PATENT OFFICE.

THOMAS W. MOORE, OF FORT WORTH, TEXAS.

SLUG-GUIDE.

1,184,980.

Specification of Letters Patent. Patented May 30, 1916.

Application filed February 8, 1916. Serial No. 76,927.

To all whom it may concern:

Be it known that I, THOMAS W. MOORE, a citizen of the United States, residing at Fort Worth, in the county of Tarrant and State 5 of Texas, have invented certain new and useful Improvements in Slug-Guides, of which the following is a specification.

My invention relates to linotype attachments and more particularly to guides for 10 taking care of the slugs as they are being discharged from the knife slug plates to the galley; and the object is to provide a simple device for causing the slugs to lie on their feet with the printing edges upward when 15 they reach the galley and to provide an inexpensive device which will not batter or mutilate the printing edges of slugs, and to provide a device which is adjustable for slugs of different lengths.

20 Other objects and advantages will be fully explained in the following description and the invention will be more particularly pointed out in the claims.

Reference is had to the accompanying 25 drawings which form a part of this application.

Figure 1 is a front elevation of the improved guide, showing the relative position as applied to the linotype machine. Fig. 2 30 is a side elevation of the same on a larger scale than Fig. 1.

Similar characters of reference are used to indicate the same parts throughout the several views.

35 The improvement herein set forth is to take the place of the device now being used for such purpose as above stated. The defect in the device now in use does not prevent satisfactorily the slugs from turning over 40 with the bottom upward instead of the printing edge. The improved guide is hung on the vise cap. A spring steel wire is bent to form an eye 3 and then laterally from the eye 3 and then downwardly to form the 45 arms 1 and 2. Any suitable screw may be used to mount the guide on the vise cap 12 so that the guide will hang with the arms 1 and 2 parallel with the right hand knife slug plate 7 and its coöperating plate 8 of 50 the linotype machine. An antifriction roller 5 is carried by the arms 1 and 2. This

roller is preferably made of fiber or rubber or of some material that will not injure the printing edges of the slugs if the slugs fall against the roller. The roller 5 is loosely 55 mounted on the shaft 6 and the shaft 6 is attached by brazing or otherwise to sleeves 4 which are slidable on the arms 1 and 2. The sleeves 4 are adjustable to any part of the arms 1 and 2 and may be supported at 60 any point on the arms by friction of the sleeves against the arms and by the tension of the arms 1 and 2 which are made of spring steel and which may be made so that the lower ends thereof would stand spread 65 farther apart than the upper ends until confined by the sleeves so that when drawn together to receive the sleeves there will be a considerable tension in the spring arms 1 and 2. The plates 7 and 8 form the usual 70 track or chute for the slugs to pass to the galley 10 where they are fed or shoved regularly by the slug lever 9 against the galley slide 11. The function of the roller is to keep the slugs in the track between the 75 plates 7 and 8 and consequently prevent the slugs from turning over as they are passing to the galley 10. The roller 5 turns freely on the shaft 6 and must be of a material which will not injure the slugs. 80

Various changes in the sizes and proportions and arrangement of the several parts may be made without departing from my invention.

What I claim, is,—

1. In a linotype machine, a protecting member comprising a spring steel wire bent to form a supporting eye and to form parallel arms, and a guide for slugs adjustably mounted on said arms, said eye being hung 90 on a suitable part of the linotype machine.

2. In a linotype machine provided with knife slug plates and a vise cap, a slug protecting member comprising a pair of tension arms substantially parallel to said plates and 95 forward of said plates and a guide roller adjustably mounted on said arms.

3. In a linotype machine, provided with a vise cap and with knife slug plates, a slug guiding member comprising a pair of arms, 100 means for mounting said arms on said vise cap so that said arms will project laterally

and forward of said slug plates, and a roller guide adjustably supported on said arms.

4. In a linotype machine provided with a vise cap and with knife slug plates, a slug guiding member comprising a pair of arms having their upper terminals formed into an eye and said arms being forward of said
- 5 plates and on the outside of said plates, sleeves adjustably supported on said arms, a shaft connecting said sleeves, and a roller 10 guide on said shaft.

In testimony whereof, I set my hand this 5th day of February, 1916.

THOMAS W. MOORE.
